ATTORNEY

UNITED STATES PATENT OFFICE

LEO M. COOPER, OF YONKERS, NEW YORK

LADY'S GARMENT

Application filed August 28, 1930. Serial No. 478,430.

This invention relates to garments such as nurse's or maid's uniforms or the like women's apparel.

The invention is directed to a garment of the character described wherein provision is made for overlapping of the front skirt portions so that by a reversal thereof, the time of use of the garment may be increased. According to this invention, the garment affords this and other advantages in a unitary, one-piece construction, wherein the skirt portion is integral with the waist portion only at the rear of the latter, and may be buttoned in overlapping position to the waist at the front thereof, both the waist portion and the skirt portions being open at the front to enable very easy donning and doffing of the garment.

Other advantages which follow from this construction are further pointed out in the following specification.

A further object of this invention is to provide a neat garment of the character described, which shall be comparatively inexpensive to manufacture, comprise few and simple parts, be easy to put on or remove from the body, easy to manipulate for reversing the front skirt portions and which shall yet be attractive in appearance, and practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawings, in which is shown one of the various possible illustrative embodiments of this invention,

Fig. 1 is a front elevational view of the garment in position on the wearer;

Fig. 2 is a partial rear elevational view of the mid-portion of the garment;

Fig. 3 is a front partial elevational view of the garment with the skirt portions thereof partially folded back;

Fig. 4 is a cross-sectional view taken on line 4—4 of Fig. 3; and

Fig. 5 is a view similar to Fig. 1, but showing the front skirt portions in reversed position.

Referring now in detail to the drawings, 10 designates a garment embodying the invention, here shown in the form of a woman's dress such as a housedress, or nurse's or maid's uniform, said garment comprising a waist portion 11 preferably adapted to be buttoned at the front thereof, by means of buttons 12, adjacent the split portion 13 and button holes 14 formed adjacent the edge portion 15. The garment may be provided with sleeves 16 of any suitable construction and a collar 17. The waist portion 11 preferably terminates at the front thereof in a lower edge portion 18 extending to the sides of the garment, said edge portion 18 preferably being gathered and stitched to decrease the length thereof whereby the garment will be fashioned to fit the wearer's body.

Extending from the rear of the waist portion and preferably integrally formed therewith is a skirt portion 20. Said skirt portion comprises a central rear portion 21 and a pair of outwardly extending portions 22 and 23. It will be noted that the outwardly extending portions 22 and 23 terminate at 80 the waistline and may be folded one over the other in reverse positions. Said portions 22 and 23 are preferably provided with bands 24 and 25 at the upper ends thereof, said bands having spaced button holes 26 and 27 85 or the like fastening means, respectively. These button holes are preferably located at the central and adjacent ends of each of said outwardly extending skirt portions 22 and 23. Sewed to the waist portion 11 on 90 both sides of said split portion thereof and adjacent the lower edge 18 thereof are buttons 30 and 31 or the like cooperating fastening means adapted to be received in the outer of said button holes 26 and 27 provided in 95 each of said skirt portions 22 and 23.

Thus, in Fig. 1, the skirt portion 22 is disposed on the inside and is buttoned to the buttons 30 and 31 and also to the lowermost of said buttons 12. The other skirt portion 100

23 is folded over the skirt portion 22 and is likewise buttoned to the buttons 30 and 31 and to the lowermost of said row of buttons 12. It will be noted that each of said skirt portions 22 and 23 covers substantially the entire front of the body so that when worn, only the skirt portion located on the outside is exposed and soiling of the inner-skirt portion is prevented.

10 The skirt portion 22 is provided with a pocket 35 located adjacent the left side thereof and the skirt portion 23 is provided with a pocket 36 located adjacent the right side thereof so that when the garment is worn in the position shown in Fig. 1, the pocket 35 is substantially hidden and the pocket 36 is exposed for use. For reversing the position of the skirt portions 22 and 23, it is merely necessary to unbutton said skirt portions as shown in Fig. 3 and then to first button the skirt portion 23 so that the same is located on the inside and to then wrap or fold the skirt portion 22 on the outer side and button the same to the buttons 30 and 31 and to the lowermost of said row of buttons 12. Thus, the time of use of said garment between washings is increased. A belt 40 may be attached to the rear of the garment at the waistline and this belt forms a continuation of the bands 24 and 25.

It will be noted that the garment may easily be put on or removed in the manner of a coat since the waist is buttoned down the front and the skirt portion may be likewise open at the front.

It will be noted that the outwardly extending portions 22 and 23 are identical and symmetrically constructed so that the skirt portion of the dress always has the same appearance, substantially, whether one or the other of the said portions is exposed, and further that the unexposed portion is always completely hidden, so that the saving of time and wear is without sacrifice as to the general neatness and appearance of the garment.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

A woman's garment having a waist portion split down the front along a substantially straight median line and having a front lower edge extending to the waistline of the

wearer, a plurality of fastening elements on the lower edge of the front of said waist, one of said fastening elements positioned near the side of the waist on one side of the split and another one of said fastening elements positioned near the side of the waist on the opposite side of said split, and a skirt portion permanently fixed to said waist portion only at the rear thereof and having oppositely extending detachable front portions free from said waist portion, each extending from one side of the garment to the other thereby covering substantially the entire lower front part of the wearer's body in reversible overlapping relation with the other front skirt portion independently of the waist portion, each of the upper edges of said front skirt portions terminating substantially at the waist line of the wearer and each of said upper edges having a plurality of complementary fastening elements positioned at opposite sides of the front skirt portion for reversibly attaching said front skirt portions to said first mentioned fastening elements on the lower edge of the front waist portion at the opposite sides thereof.

In testimony whereof I have affixed my signature August, 1930.

LEO M. COOPER.
